UNITED STATES PATENT OFFICE.

WALTER A. RICHMAN, OF EGG HARBOR, NEW JERSEY.

RECORD-LIFTING DEVICE.

1,390,546.

Specification of Letters Patent. Patented Sept. 13, 1921.

Application filed July 27, 1920. Serial No. 399,314.

To all whom it may concern:

Be it known that I, WALTER A. RICHMAN, a citizen of the United States, residing at Egg Harbor, in the county of Atlantic and State of New Jersey, have invented certain new and useful Improvements in Record-Lifting Devices, of which the following is a specification.

This invention relates to sound reproduction apparatus and more particularly to a means for lifting disk records from the turntables of such apparatus. Phonographs and the like employing flat disk records have been heretofore so constructed that more or less difficulty is experienced in lifting the record from the flat turntable upon which it is supported during the reproduction period, it being necessary to engage one's finger nails beneath the periphery of the record with the attendant likelihood of slipping of the finger and scratching of the record.

Also in the use of the ordinary phonograph, it is practically impossible to change records while the turntable is rotating and it is therefore necessary to apply the brake device whenever it is desired to make this change. While it may not generally be desired to change records while the turntable is rotating, nevertheless it may be found an advantage to do so and the present invention therefore contemplates the provision of means for lifting the record from the turntable regardless of the position of rotation of the turntable or whether the turntable be stationary or rotating.

Another object of the invention is to so construct the device that in its operation the record will be lifted evenly and supported in position above the turntable a sufficient distance to permit of the passage of one's fingers beneath the periphery of the record for the removal thereof.

Another object of the invention is to provide a device for the purpose stated which may be applied to any of the ordinary types of sound reproduction apparatus which employ flat disk records.

In the accompanying drawings:

50. Figure 1 is a top plan view of the device of the present invention embodied in a phonograph of a well-known type;

Fig. 2 is a vertical transverse sectional view taken in a plane passing through the axis of the turntable;

Fig. 3 is a perspective view illustrating the parts comprising the device partially disassembled;

Fig. 4 is a vertical longitudinal sectional view through the operating means of the device.

In the drawings the numeral 1 indicates in general the box or cabinet of any sound reproducing apparatus employing a disk record, and the numeral 2 indicates the 65 motor driven spindle having the tapered upper end 3 to which is frictionally removably fitted the hub 4 of the record turntable which is indicated in general by the numeral 5.

The turntable 5 is provided centrally with a depressed or sunken portion 6, and a face 7 of felt or any other suitable friction material is applied to the upper side of the table as is customary. The sunken 75 or depressed portion 6 of the turntable normally receives and houses the upper portion of the lifting means for the disk record, which record is indicated in the drawings by the numeral 8.

The lifting means above referred to comprises a circular plate 9 provided upon its upper surface with a facing 10 which may be of the same material as the facing 7, and the said plate 9 is formed axially with 85 an opening 11 to register with the openings in the hub of the turntable 5 and to accommodate the upper end 3 of the spindle 2. The plate 9 is held for rotation with the turntable by means of pins 12 which project 90 downwardly from the under side of the plate preferably at or adjacent its periphery and fit loosely slidably through openings 13 formed in the bottom of the depressed portion 6 of the turntable. At their lower 95 ends these pins support an annulus 14 which is concentric to the axis of the turntable. While as stated the plate 9 is connected for rotation with the turntable 5 and normally assumes the lowered position shown in Fig. 2 of the drawings, in which position it is housed within the depressed portion 6 of the turntable with the upper surface of its facing 10 substantially flush with the surface of the facing 7 of the turntable, it will be evident that any means acting with pressure in an upward direction against the annulus 14 would serve to elevate the plate 9 regardless of the position 105 of rotation of the turntable or whether the 110

turntable was stationary at the time or rotating. Consequently, by exerting pressure in an upward direction against the ring 14, a record supported upon the turntable 5 5 will be lifted in the upward movement of the plate 9 to such position that one's fingers may be readily inserted beneath its periphery for the purpose of entirely removing it from the apparatus.

10 In the drawings I have illustrated one means which may be employed for the purpose of coaxing with the ring 14 to elevate and lower the lifting plate 9 and this means is best shown in Figs. 3 and 4 of the drawings and includes a small shaft 15 which if desired may be formed from wire bent to the required form and to provide crank portions 16, 17 and 18. The shaft 15 is journaled in suitable bearings 19 of simple construction 15 20 which may be readily secured in place upon the bottom board of the case or cabinet 1, and the shaft is so mounted that its portion between its cranks 16 and 17 will extend relatively close to the spindle 2 with the said 25 cranks located at diametrically opposite sides of the spindle and equidistantly spaced therefrom and furthermore located immediately below the annulus 14. Anti-friction rollers 20 and 21 are loosely mounted upon the 30 crank portions 16 and 17 respectively and are designed to ride against the under side of the annulus 14 when the shaft 15 is rotated or rocked so as to swing the cranks in an upward or downward direction, the annulus 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

casing 26, and this spring is provided between its ends with a downwardly deflected portion 31 lying close to the rod or bar 24. An anti-friction roller 32 is mounted upon the upper side of the bar or rod 24 and is designed to ride against the under side of the spring 29 and it will be evident that when the rod or bar 24 is shifted by pressing against either of its ends, the said roller 32 will ride beneath the downwardly deflected portion 31 of the spring 29 until it assumes a position at the opposite side of the said portion. Thus the spring 29 offers a suitable resistance to shifting movement of the member 23 and serves also to maintain this member in either of its positions of shifting movement. A suitable cover 33 may be provided for the casing 26. The crank 18 is located at that end of the shaft 15 which is located next adjacent the actuating member 23 and carries an anti-friction roller 34 which works in a suitable guide 35 depending from the rod or bar 24. It will be understood, of course, that the guide or yoke 35, the crank 18 and its anti-friction roller 34, the spring 29, and the member 23, except for the button carrying ends of the latter, are housed within the casing 26 so that the actuating mechanism as a whole does not present an unsightly appearance.

In the use of the device, the lifting plate 9 being in the lowered position shown in Fig. 2, a record may be placed upon the turntable and the record reproduced in the usual manner. After the record has been placed, the tone arm of the apparatus is swung clear of the turntable in the usual way and then the right hand end of the actuating member 23 in Fig. 1 of the drawings may be pressed so as to shift the member and rock the shaft 15 to swing the cranks 16 and 17 in an upward direction. As the cranks are thus moved, they will ride against the annulus 14 thus lifting the plate 9 and elevating the record bodily above the turntable so that the operator's fingers may be readily inserted beneath the periphery of the record.

Having thus described the invention, what is claimed as new is:

1. The combination with the turntable of a sound reproduction apparatus, of a record lifting plate associated with the table, an annulus located beneath the table and having connection with the plate through the table, a rock shaft having crank portions to ride against the annulus when the shaft is rocked in one direction, and thus move the annulus in an upward direction, and means for rocking the said shaft, the said means comprising a shiftable member having a guide, the said shaft having a crank engaging the guide.
2. The combination with the turntable of a sound reproduction apparatus, of a record-

- lifting member associated with the table, an annulus located beneath the table and having connection with the said member through the table, a rock shaft mounted beneath the table substantially diametrically thereof and having crank portions arranged to be elevated into coöperative engagement with the annulus when the shaft is rocked in one direction and thereby elevate the said 10 annulus and the said record-lifting member, the shaft extending at one end beyond the periphery of the turntable, a manually shiftable actuating member located in juxtaposition to the said end of the shaft, a guide 15 carried by the said actuating member, and a crank upon the said end of the shaft working in the guide.
3. The combination with the turntable of a sound reproduction apparatus, of a record-lifting member associated with the table, an annulus located beneath the table and having connection with the said member
- through the table, a rock shaft mounted beneath the table substantially diametrically thereof and having crank portions arranged to be elevated into coöperative engagement with the annulus when the shaft is rocked in one direction and thereby elevate the said 25 annulus and the said record-lifting member, the shaft extending at one end beyond the periphery of the turntable, a manually shiftable actuating member located in juxtaposition to the said ends of the shaft, a guide carried by the said actuating member, a crank upon the said end of the shaft working 30 in the guide, and means for holding the actuating member in its positions of shifting movement comprising a yieldable abutment, and means carried by the actuating member 35 for coaction with the opposite sides of said 40 abutment.

In testimony whereof I affix my signature.

WALTER A. RICHMAN. [L. s.]
